GAME APPARATUS

Charles D. Shannon, Florence, Mass.

Application December 24, 1942, Serial No. 469,972

2 Claims. (Cl. 273—35)

This invention relates to a game apparatus of general utility but more particularly adapted to a putting game with a golf ball.

In the embodiment shown, the parts are in such relative proportion as to be suitable for an outdoor game in which the usual golf club and ball are used. The apparatus, however, is of convenient portable size and either singly or in combination with other devices of like character may be set down on a putting green or other reasonably level base for playing the game.

The advantages of this game apparatus are that it not only affords means for amusement and competitive skill in putting but also serves as a practice implement, the use of which either in competition or in solo sufficiently simulates the actual conditions for putting into a cup as to greatly improve the player's putting skill. It has the further advantage of providing such conditions readily at places remote from a prepared golf field and without disturbance of the base or field on which it is used.

In the drawing, which illustrates a preferred embodiment of the apparatus.

Fig. 1 is a plan view of the complete device;

Fig. 2 is a longitudinal section along line 2—2 of Fig. 1;

Fig. 3 is a perspective view of the same; and

Fig. 4 is a view of the arrangement of several said devices on a playing field.

Referring more particularly to the drawing, the apparatus comprises a frame which may be suitably made up from relatively long and narrow strips of material such as wood nailed or otherwise secured together to form a unitary structure which is portable for being set down on any relatively smooth or level area as a playing field. In the formation of the frame two such narrow strips of wood, indicated at 1 and 2 are arranged in parallel relation and set on edge, so as to form the side walls of a relatively narrow and long straight channel 3 through which a golf ball may be putted. The frame should provide other similar putting channels formed as shown by the arrangement of the strips 4 and 5 which constitute the walls of a putting channel at 6.

The strips or wall pieces 1, 2, 4 and 5 or further strips if additional channels are provided, are all held together by suitable tie strips 7 and 8 which lie flat across the top edges of the first named strips and may be nailed thereto. As shown, these connecting strips such as 7 and 8 at the top of the wall pieces form the sole means for holding the wall pieces together whereby the bottom of the several putting channels are left

free of obstructions when the frame is placed upon a putting green or other base. It will be understood that the height of the vertical walls of the putting channels will be sufficient to allow an ordinary golf ball such as indicated at B to roll therethrough without interference from the tie strips 7 and 8 as shown in Fig. 2. The ends of the strips 1 and 4 are each preferably provided as shown with cleats 9, 10, and 11, 12, both to reinforce said ends and also to provide a slightly wider base therefor than would be furnished by the thickness of the strip itself. The inner strips 2 and 5 are provided with such end cleats 13 and 14 only at the wider end of the frame.

The putting channels 3 and 6 formed by the aforesaid strips are preferably arranged to diverge from one end of the frame to the other so as to impart to the frame a V-shaped contour. Also at the narrow end of said frame the channels 3 and 6 are slightly spaced from one another so that a ball may be putted directly through said frame along its longitudinal axis and between said channels 3 and 6 without going through either of them. In other words, at the narrow end of the frame there is an entrance for the ball to be putted, indicated at 15, and another entrance in line therewith at 16, as well as the side entrances 17 and 18 into the respective channels 3 and 6. The outside walls or strips 1 and 4 for the frame are preferably extended beyond the corresponding ends of the inner strips 2 and 5 so as to provide at the wide end of the frame, portions at 19 and 20 against which banking shots may be made in putting the ball towards the said entrances of said channels 3 and 6.

It will be readily understood that many different sets of rules of play may be formulated for creating a competitive putting game by the use of the apparatus as shown, and that said apparatus may be used either singly or in combination with other devices of similar character arranged on a playing field in different positions to enhance interest in the game. The apparatus also may be used by a solo player to improve his putting skill.

Referring to Fig. 4 which illustrates one manner in which the apparatus may be used in a game, I have shown four of said devices F set down on a playing field. The narrow ends of each of the frames may be pointed outwardly and the wide ends facing towards the center. A short distance beyond the narrow end of each frame F may be marked a line P behind which

the ball may be placed in any desired position of starting a putt through the frame. The rules may provide that the ball shall be played through the several frames in the direction of the dotted line and arrows thereon as indicated in Fig. 4 so that the ball will have to be played successively through each frame and through each channel or space therethrough. The number of strokes required in putting the ball from the starting position around through the frames and back again may be counted as the score for the game.

I claim:

1. In a game apparatus for use with a golf ball in a putting game, a V-shaped frame comprising a pair of parallel spaced apart wall pieces at one side of the frame, a second pair of parallel spaced apart wall pieces at the other side of said frame, means for holding said several wall pieces together in their relative positions to constitute said frame each said pair of wall pieces forming a relatively long and narrow putting channel therebetween, said pairs of wall pieces being arranged in divergent relation to one another for giving said frame its V-shape, the outer wall piece of each pair being extended slightly beyond the adjacent end of its respective inner wall piece, the converging ends of the two outer wall pieces being spaced apart to provide a putting opening; and the converging ends of the two inner wall pieces being spaced apart

5 to provide a second putting opening in line with said first named putting opening, said second named putting opening being between the entrances to the separate and divergent putting channels of said frame.

2. In a game apparatus for use with a golf ball in a putting game, a V-shaped frame comprising a pair of parallel spaced apart wall pieces at one side of the frame, a second pair of parallel spaced apart wall pieces at the other side of said frame, tie pieces connected across the top edges of said several wall pieces and forming the sole means of holding said wall pieces together in the frame, each said pair of wall pieces forming a relatively long and narrow putting channel therebetween, said pairs of wall pieces being arranged in divergent relation to one another for giving said frame its V-shape, the outer wall piece of each pair being extended slightly beyond the adjacent end of its respective inner wall piece, the converging ends of the two outer wall pieces being spaced apart to provide a putting opening, and the converging ends of the two inner wall pieces being spaced apart to provide a second putting opening in line with said first named putting opening, said second named putting opening being between the entrances to the separate and divergent putting channels of said frame.

CHARLES D. SHANNON.
